UNITED STATES PATENT OFFICE.

WILLIAM R. GORRELL AND HENRY BARKSCHAT, OF LOS ANGELES, CALIFORNIA.

RAIL CHAIR.

Application filed October 26, 1922. Serial No. 597,198.

To all whom it may concern:

Be it known that we, WILLIAM R. GORRELL and HENRY BARKSCHAT, citizens of the United States, residing at Los Angeles, in the county of Los Angeles and State of California, have invented certain new and useful Improvements in Rail Chairs; and we do declare the following to be a full, clear, and exact description of the invention, such as will enable others skilled in the art to which it appertains to make and use the same.

This invention relates generally to rail chairs, but particularly to rail fastening devices for rail chairs and is an improvement upon the device disclosed in Patent No. 1,402,760, granted on January 10, 1922 to the present inventors.

The device disclosed by the aforesaid patent consists of a rail supporting member provided with a pair of vertical openings in which are disposed expandable rail spike clamps. These clamps are provided with eccentrically disposed spike-receiving openings and are reversible in the openings of the supporting member, but are not invertible so that they have to be inserted in the openings of the supporting member with certain of their ends uppermost, and consequently in order for the device to be used, the supporting member must be placed so as to have one of its sides uppermost.

The present invention is an improvement upon the above described device, because the rail supporting member may be used with either of its sides uppermost and the spike-receiving clamps are not only reversible in the openings in said member but are also invertible so that they may be inserted with either of their ends uppermost.

The improvements forming the subject matter of the present invention render the device as a whole extremely simple, cheap and durable in construction, and the patentable novelty in the improved device resides in the unique combination and arrangement of parts and the various details of construction which are hereinafter fully described and claimed and illustrated in a

practical embodiment in the accompanying drawing.

In the accompanying drawing which forms a part of this specification and throughout which similar reference characters are used to designate corresponding parts:—

Fig. 1 is a side elevation, partly broken away and in section, of a rail chair in which the improvements forming the subject matter of the present invention are embodied;

Fig. 2 is a top plan view, partly broken away and in section, of the improved rail chair.

Fig. 3 is a perspective view, with a portion broken away, of the rail chair proper or the rail supporting member.

Figs. 4 and 6 are side elevations of the complementary parts of one of the rail spike-receiving clamps; and

Figs. 5 and 7 are top plan or end views of the complementary parts of the rail spike-receiving clamp illustrated in Figs. 4 and 6 respectively.

In the drawing above briefly described, the numeral 1 designates as a whole a rail-supporting member. This is preferably of the I-beam type having parallel flanges 2 and 3 integrally connected by a web 4. Insofar as the improvements forming the subject matter of the present invention are concerned, the rail-supporting member 1 does not have to be of the I-beam type, but it can be of any other type that is desired.

The rail-supporting member 1 is provided with a pair of spaced openings which extend vertically therethrough from one side thereof to its other side. When the member 1 is of the I-beam type, such as illustrated in the drawing, these vertical openings are formed by means of aligned substantially H-shaped openings 5 in the flanges 2 and 3 and openings or slots 6 in the web 4, the openings or slots 6 communicating at their ends with the aligned openings 5 in the flanges 2 and 3.

The opposite edges of the openings or slots 6 are provided with concaved portions

7. These portions 7 are located midway between the opposite sides of the member 1, or in other words, midway between the parallel flanges 2 and 3 of the member 1.

8. The vertical openings which extend through the rail-supporting member 1 are intended to receive expandible rail spike-receiving clamps. These clamps are each formed in two parts or sections and one section 10 may be considered as the complement of the other. When the complementary sections of the clamps are fitted together their cross-sectional contour is of substantially H-shape, corresponding with the shape 15 of the openings 5.

In Figs. 4 and 5 of the drawing, the numeral 8 designates one of the sections or parts of one of the rail spike-receiving clamps and in Figs. 6 and 7 the complementary section of the clamp is designated by the numeral 9. From these views, it will be seen that the H-shape contour of the clamp is formed by providing channels 10 in the side edges of the sections 8 and 9, 25 these channels 10 being designed to receive the edges of the slots or openings 6 in the web 4 of the rail-supporting member 1. The channels 10 of both sections 8 and 9 are of the same depth.

30. The inner sides of the sections 8 and 9 are also provided with channels 11. These channels 11 are arranged in opposing relation to each other so that they form passages 12 extending vertically through the 35 clamp from one end thereof to the other. These passages 12 are disposed eccentrically with respect to the central axes of the clamps, since the channels 11 in the clamp sections 9 are deeper than the channels 11 40 in the sections 8. The channels 12 are designed to receive the spikes which anchor a rail to the supporting member 1 and therefore in order to provide a means whereby the spikes may be held in place when once 45 driven in said passages, the latter at their opposite ends are provided with bends 13 which are formed by curved projections 14 located in the channels 11 of one section and oppositely disposed depressions 15 in the 50 channels 11 of the other section. This construction causes the spikes when driven into the passages 12 to be bent to fit the projections 14 and depressions 15.

55. Formed upon the sections 8 and 9 of the rail spike-receiving clamps and located within the channels 10 of said sections are projections 16. These projections 16 are disposed midway between the opposite ends of the sections 8 and 9 and are intended to 60 fit in the notches 7 formed in the edges of the slots or openings 6 of the web 4 of the rail supporting member 1.

In using devices constructed as described in the foregoing, a number of the rail chairs

are secured to a wooden or concrete tie or imbedded in a roadbed in a steel tie in any suitable manner. In arranging the supporting members 1 in place upon the ties or the roadbed, they may be placed with either side uppermost since they are invertible. The two-part or two-section spike-receiving clamps should then be inserted, when in contracted condition, into the vertical openings in the rail supporting members 1. In inserting the clamps in the openings in the rail supporting members 1, they may be placed with either of their ends uppermost since they are invertible in said openings, but since the passages 12 extending therethrough are eccentrically disposed, the clamps should be inserted in the openings in the supporting members 1 so that said passages 12 will be in proper positions to receive the spikes by which a rail is fastened to the members 1. After the clamps are in place, and the rail, such as designated by the letter R in Fig. 1, is placed upon the members 1, spikes S should be driven into the passages 12. When the spikes S are driven into the passages 12 of the clamps, the sections 8 and 9 thereof will be expanded and the projections 16 will be inserted into the notches 7 in such a manner that the clamps will be locked in place in the openings through the member 1 and cannot be moved therefrom until after the spikes S are withdrawn from the passages 12.

From the foregoing description, taken in connection with the accompanying drawing, the construction, use and operation of the device will be readily understood without requiring a more extended explanation.

It is obvious that certain changes in form, proportion, and in the various details of construction may be made without sacrificing any of the advantages or departing from the principle of the invention, and it is therefore to be understood that such changes may be made within the meaning and scope of the appended claims.

What is claimed is:

1. In a rail chair, the combination of a rail-supporting member having an opening extending vertically therethrough, an expandible, invertible, rail spike-receiving clamp disposed in said opening, and inter-engaging elements carried by said member and said clamp for locking the latter in said opening when in expanded position, said elements being positioned upon said member and said clamp so that the latter may be inverted in said opening.

2. In a rail chair, the combination of a rail-supporting member having an opening extending vertically therethrough, the opposite edges of said opening being provided with opposed notches, said notches being

located midway of the ends of said opening, an expansible, invertible rail spike-receiving clamp disposed in said opening, the opposite edges of said clamp being provided with projections adapted to fit into said notches when said clamp is expanded, said projections being located midway of the

ends of said clamp so that the latter may be inverted in said opening.

In testimony whereof we have hereunto ¹⁰ affixed our signatures.

WILLIAM R. GORRELL.
HENRY BARKSCHAT.
